US00D381637S

United States Patent [19]

Haider et al.

[11] Patent Number: **Des. 381,637**[45] Date of Patent: ****Jul. 29, 1997**

[54] **ELECTRONIC CIRCUITRY HOUSING PANEL**

[75] Inventors: **Robert Sala Haider**, San Diego, Calif.; **Ellen Martz**, Gaithersburg, Md.; **Andrew Zoolakis**, La Costa, Calif.

[73] Assignee: **Hughes Electronics**, Los Angeles, Calif.

[**] Term: **14 Years**

[21] Appl. No.: **50,906**

[22] Filed: **Feb. 29, 1996**

[51] LOC (6) Cl. **13-99**

[52] U.S. Cl. **D13/184**

[58] Field of Search D13/177, 164,
D13/184; 361/801; D14/115; 174/50

[57] **CLAIM**

The ornamental design for an electronic circuitry housing panel, as shown and described.

DESCRIPTION

FIG. 1 is a perspective view of an electronic circuitry housing of the present invention;

FIG. 2 is an enlarged front view of an electronic circuitry housing of the present invention;

FIG. 3 is a back view of an electronic circuitry housing of the present invention;

FIG. 4 is a top view of an electronic circuitry housing of the present invention;

FIG. 5 is a left side view of an electronic circuitry housing of the present invention;

FIG. 6 is a right side view of an electronic circuitry housing of the present invention; and,

FIG. 7 is a bottom view of an electronic circuitry housing of the present invention.

The broken line showing of a housing in FIG. 1 is for illustrative purposes only and form no part of the claimed design.
